UNITED STATES PATENT OFFICE.

ALAN K. GILLESPIE, OF KENOSHA, WISCONSIN, ASSIGNOR TO FRANCES K. GILLESPIE,
OF KENOSHA, WISCONSIN.

TRACK-DOOR.

1,072,600.

Specification of Letters Patent.

Patented Sept. 9, 1913.

Application filed September 10, 1912. Serial No. 719,534.

To all whom it may concern:

Be it known that I, ALAN K. GILLESPIE, a citizen of the United States, and residing in the city of Kenosha, in the county of 5 Kenosha and State of Wisconsin, have invented or discovered new and useful Improvements in Track-Doors, of which the following is a specification.

My invention consists in a new and improved track-door for refrigerators or other storage compartments wherein the goods, such as sides and quarters of meat, are suspended from wheeled hangers mounted on a track rail or rails extending from without 15 into the refrigerator through an opening in the wall of the latter above and communicating with the regular door-way.

In practice it has been found difficult to provide a closure for the track-opening 20 which will prevent air-leakage. Sliding shutters and swinging doors have been used, as has also a plug for the opening which is inserted and calked to obtain a tight joint. The last named method of closure, although 25 efficient in preventing air-leakage, requires an expenditure of too much time and labor in operation to be satisfactory.

My object is to provide a closure for the track-opening which will operate automatically 30 in unison with the door proper and which, when closed, will effectually prevent air-leakage.

I effect the end in view by forming a projection on the wall of the compartment 35 which extends laterally into the tracking-opening against the end of which the track-rail abuts and is preferably rigidly secured. A compressible packing is preferably introduced between the upper portion of the 40 track-rail and the end of said projection to permit the hanger wheel to pass through the track-opening.

I form the closure or track-door with an inwardly extending tapered plug, similar to 45 the usual plug of a refrigerator door, which fits into the track-opening. I prefer to provide the track-door with an overlap to seal the edge of the opening. The overlap of the track-door is brought under the track-rail at an incline and the overlap and plug 50 are brought over the track-rail at an incline to provide sufficient clearance, even where said door sags, for opening and closing the track-door. The plug is recessed to extend 55 over the top of and parallel with the ex-

posed vertical face of the track-rail and is provided with packing secured to the face of the plug to engage the top and side face of the rail to obtain a tight closure. I prefer to make the track-door integral with 60 the main door, but it may, if desired, be a separate element.

Other novel features of structure and arrangement of parts will appear from the 65 following description.

In the accompanying drawings, Figure 1 is a broken perspective of the front of a refrigerator fitted with my invention, the door being shown partly open; Fig. 2 is an enlarged front elevation showing the track-opening the position of the closure or track-door being shown in dotted lines; Fig. 3 is a similar view of the track-door, one corner of the same being shown broken away to show the plug, and the track-rail and packing being shown, for the sake of clearness, in dotted lines.

The following is a detailed description of the drawings:

A represents the outer wall of a refrigerator or storage-compartment having the usual doorway B above which and communicating therewith I provide the track opening C which is substantially of inverted L-shape, the wall of the refrigerator projecting inwardly at the bottom of the opening as at 1. The projection 1 has an inclined upper surface and is provided with a ledge 2 which extends under the track-rail D. The track-rail D is a metal bar, permanently 80 supported in any convenient manner and extending through the track opening C bearing against the projection 1 and preferably rigidly secured thereto. The upper portion of projection 1 is cut away to form 85 a seat for a packing 3 of felt or other compressible material which is interposed between the track-rail D and the end of projection 1 to prevent the leakage of air along 90 that side of the track, and permit the passage of the flange of the hanger wheel, as shown in Fig. 2. The top of track-rail D is below the top of projection 1. The packing 3 is preferably extended somewhat 95 above the top of track-rail D being pressed down by the flange of wheel of the hanger E, Fig. 2, as the hanger passes along said track-rail through the track-opening C.

F is the door which closes the doorway B and which is provided with the usual in- 110

wardly extending tapered plug 4 which fits into said doorway and is preferably hollow and packed with non-heat-conducting material, such as felt.

5 is the overlap of the door which seals the edge of the doorway when the door is closed.

G is the track-door, or closure for the track-opening C, and is preferably an integral upward extension of the door F provided with an inwardly extending tapered plug 6, which is a continuation of the plug 4 and of substantially inverted L-shape to fit the opening C. As shown in the drawings, the left side of the plug 6 is recessed at 7 to accommodate the projection 1 and the track-rail D. The vertical edge of said recess 7 is provided with a packing or plate 8, of rubber or other compressible material secured to the face of plug 6 and bearing snugly against the face of track-rail D when the track-door is closed to prevent air-leakage. In the angle of the recess 7 the plug 6 is extended to form an angular block 25 or step 7^a to fit over the top of track-rail D, the lower face of said block being inclined to provide clearance in opening and closing the track-door and provided with a packing or plate 8^a to bear upon the top of said track-rail to prevent air-leakage.

The exterior edge of the track-door G is provided with an overlap 9 which, where the track-door is integral with the door F, is a continuation of the overlap 5 of said door.

35 Said overlap 9 extends about the edge of the track-door to seal the crack between the track-door and the track-opening except along the top and exposed side face of the track-rail D where said overlap 9 is omitted and the packing 8 and 8^a relied upon to prevent air-leakage. The overlap 9 passes under the track-rail D at a downward incline, as at 10, to provide clearance in opening or closing the track-door, and merges into the 45 overlap 5 of the door F as by step 11. The portion 12 of the overlap 9 which seals the upper edge of projection 1 begins at a point adjacent to the upper inner edge of track-rail D and extends at an upward incline to clear 50 the track-rail D in opening and closing the track door. This prevents catching or binding, even when the door is sagged. The inverted L-shape of the track-opening provides sufficient clearance for the hanger E 55 even should the same swing or rock laterally in passing through the opening C.

It is evident that my track-door effects a complete closure of the track-opening, the plug and overlap of said door fitting into 60 and sealing the track-opening except where the same is effected by the packing 3, 8 and 8^a. Where the track door is made integral with the main door, the former is automatically opened and closed by the main door, so 65 that no delay or inconvenience in moving

goods results. My structure adds little or nothing to the cost of the refrigerator or compartment, tightly seals the track-opening against air-leakage and effects a great saving in time and labor.

What I desire to claim is:—

1. In combination with a storage compartment provided with a main doorway and an opening for the passage of the wheeled hanger communicating therewith, a projection of the wall of said compartment partially separating said doorway from said opening, a track-rail extending into said compartment contacting with the end of said projection, and a swing door adapted to close said doorway and having an integral extension adapted to close said opening. 70

2. In combination with a storage compartment having a main doorway and an opening for the passage of the wheeled hanger communicating therewith, a projection of the wall of said compartment partially separating said doorway from said opening, said projection being provided with a ledge, 75 a track-rail extending into said compartment resting on said ledge and its side contacting with the end of said projection, a swing door adapted to close said doorway and having an integral extension adapted 80 to close said opening, said door being provided with an overlap which abuts against the upper and lower outer face of said projection. 85

3. In combination with a storage compartment having a main doorway and an annular opening for the passage of the wheeled hanger communicating therewith, a projection of the wall of said compartment partially separating said doorway from said opening, said projection having a downwardly and outwardly inclined top surface, a track-rail, its side contacting with the end of said projection, the top of said track-rail being below said inclined surface and 100 a door for said main doorway having an integral extension adapted to close said opening, the overlap of said door being adapted to abut against the face of said projection above the level of said track-rail. 105

4. In combination with a storage compartment having a main doorway and an opening for the passage of the wheeled hanger communicating therewith, a projection of the wall of said compartment partially separating said doorway from said opening, said projection having a downwardly and outwardly inclined top surface, a track-rail, its side contacting with the end of said projection, said rail being below said inclined 110 surface and above the bottom of said projection, and a door provided with an overlap and adapted to close said main doorway and having an integral extension adapted to 115 close said opening, the overlap of said door 120

125

130

abutting against said projection above and below said track-rail.

5. In combination with a storage compartment provided with a main doorway and an opening for the passage of the wheeled hanger communicating therewith, a projection of the wall of said compartment partially separating said doorway from said opening, a track-rail extending into said compartment and its side contacting with the end of said projection, a door provided with an overlap adapted to close said main doorway and having an integral extension adapted to close said opening, said overlap extending at an incline above said track-rail when said door is closed to provide clearance in opening and shutting the door.
6. In combination with a storage compartment provided with a main doorway and an opening for the passage of the wheeled hanger communicating therewith, a projection of the wall of the compartment partially separating said doorway from said opening, a track-rail extending into said compartment and its side contacting with the end of said projection, a door provided with an overlap and adapted to close said main doorway and having an integral ex-

tension adapted to close said opening, said overlap extending at an incline below said track-rail when said door is closed to provide clearness in opening and shutting the door.

7. In combination with a storage compartment provided with a main doorway and an opening for the passage of the wheeled hanger communicating therewith, a projection of the wall of the compartment partially separating said doorway from said opening, a track-rail extending into said compartment and its side contacting with the end of said projection, a door provided with an overlap and adapted to close said main doorway and having an integral extension and adapted to close said opening, said overlap extending at an incline above and below said track-rail when said door is closed to provide clearance in opening and shutting the door.

Signed at Kenosha, Wisconsin, this 7th day of September 1912.

ALAN K. GILLESPIE.
